DIAPER

Louis I. Medoff, Cambridge, Mass.

Continuation of application Serial No. 723,920,
January 24, 1947. This application March 6,
1947, Serial No. 732,864

2 Claims. (Cl. 128—287)

1

This invention relates to an improved diaper which is especially, though not exclusively, adapted for use by an infant.

One of the objects of the invention is to provide a novel diaper having an absorbent pad and a pad-holding or body member adapted to be applied to the body of the infant and by which the pad is held in proper position, together with a protective shield element of impervious material interposed between the pad and the body member to protect said body member against any moisture that may be absorbed by the pad, so that the body member will always be dry.

A further object of the invention is to provide a diaper of the above type with an absorbent pad that is readily removable from the body member so that when the pad becomes soiled, it can easily be removed and replaced by a fresh dry pad.

Another object of the invention is to provide a diaper of this type in which the protective shield is in the form of an envelope of impervious material that is readily removable from and replaceable in the body member, and which is so made as to receive within it the absorbent pad, said envelope functioning to protect the body member from contact with the pad while permitting the infant's excretions to be received by the pad.

Another object of the invention is to provide a diaper of the above type which is so constructed that outside the opening of the pocket not only the entire outside surface thereof, but also all of the inside surface which has contact with the skin of the infant except that defined by the opening of the pocket will be kept dry at all times.

In the drawings wherein there is shown a selected embodiment of the invention,

Fig. 1 is a view with parts broken out, showing a diaper embodying the invention.

Fig. 2 is a section on the line 2—2, Fig. 1.

Fig. 3 is a view of the envelope of impervious material.

Fig. 4 is a view of the absorbent pad.

Fig. 5 is a sectional perspective view taken on the line 5—5, Fig. 1.

Fig. 6 is a perspective view showing the shape assumed by the diaper when it is applied to an infant.

The diaper herein shown comprises a body member 1 which is of a shape to pass through the crotch and up the back and front of the infant, said member being arranged on the infant

2

with the end portion 2 at the back and the end portion 3 at the front. Any suitable means may be used to detachably secure together the side edges of the end portions 2 and 3 after said member has been placed on the infant, safety pins 4 being shown in Fig. 4 for this purpose.

The body member is preferably made of some soft, smooth-surfaced fabric which will have no irritating effect on the skin of the infant. Said body member 1 is made with a pocket 5 intermediate of its end portions 2 and 3, which pocket is provided with an opening 13 on the inside face of said body member. The body member may conveniently be made of two plies of fabric, 8 and 9, which are stitched together at the edge, as seen at 10, and the pocket 5 can be formed by stitching the two plies together by two widely spaced transversely extending lines of stitching 11 and 12. The inside fabric ply 8 is formed with an opening 13 leading to the pocket 5 and which provides access to said pocket. The dimension of the pocket opening 13 both longitudinally and transversely of the body member is greater than that of the pocket 5, and said opening is preferably situated substantially centrally of the pocket.

Situated within the pocket 5 is a pad 14 of absorbent material which is exposed through the pocket opening 13, and interposed between the pad and both plies 8 and 9 of the body member is a protective member of impervious material which protects the body member from any moisture that may be absorbed by the pad 14. Such protective member may conveniently be in the form of an envelope 15 of a size to be readily received in the pocket 5 and which has an opening 16 in one side that registers with the pocket opening 13, but which is no larger than said opening 13. The envelope 15 may be made of any flexible material that is waterproof or impervious to moisture.

When the envelope containing a pad 14 is in place within the pocket 5, as shown in Figs. 1, 2 and 5, the material of the envelope protects both the inside ply 8 and the outside ply 9 from contact with the pad. Moreover if the openings 13 and 16 are of the same size as shown in the drawings, no portion of the of the impervious envelope 15 will be exposed and the body of the infant will thus be protected by the inner ply 8 of the body member against contact with the protective envelope.

The registering openings 13 and 16 are so positioned that when the body member is placed on the infant and the two end portions 2 and 3 are

fastened together, said openings are properly placed so the excretions from the infant will pass through them and will be absorbed by the pad 14. Because of the impervious character of the envelope, none of the moisture absorbed by the pad will be transferred to the body member 1 and the latter will therefore remain dry at all times, so that the only wet surface that can come into contact with the infant is that portion of the pad which is exposed through the registering openings 13 and 16.

The envelope 15 is separable from the body member and may be removed from or replaced in the pocket 5 through the pocket opening 13.

The pad 14 is also separable from the envelope and can be removed from or replaced in the envelope through the envelope opening 16.

The pad may also be in the nature of a single service pad which can be discarded after it has become soiled, or it may be a washable pad that can be washed and hence used over and over again.

An infant wearing this improved diaper will always be dry to carry or hold because even if the pad becomes wet, the outside ply 9 of the body member will remain dry due to the interposition of the impervious envelope between it and the wet pad. Furthermore, the entire surface of the inside ply 8 of the body member that has contact with the skin of the infant will also remain dry because the inside face of the envelope protects such inside ply 8 from contact with the wet pad.

When the pad becomes wet, the only wet surface that can contact the skin of the infant is that exposed through the opening 16 of the envelope.

After the pad 14 has become soiled, the envelope and soiled pad may be easily removed from the body member, and the soiled pad removed from the envelope and replaced by a fresh dry pad, after which the filled envelope can be replaced in the pocket.

This application is a continuation of application No. 723,920 filed January 24, 1947.

I claim:

1. A diaper comprising an elongated body member shaped to pass through the crotch and up the front and back of an infant, said body member comprising two plies of fabric which are stitched together along opposite side edges and also along two widely separated transverse lines to form between them a pad-holding pocket, the inner ply which contacts with the infant having a pocket opening, the dimensions of which both lengthwise and transversely of the body member are less than that of the pocket, a protective en-

velope loosely received within the pocket but unattached to the body member and removable from the pocket through the pocket opening, said envelope having inner and outer sides formed of material which is impervious to water and having an opening in the inner side which is of the same size as the pocket opening and registers therewith, the inner ply of the body member covering all of the inner side of the envelope surrounding the opening therein, and a pad of absorbent material removably retained in the envelope, a portion of said pad being exposed through the registering openings, said envelope providing an impervious shield between the pad and both the inner and outer plies of the body member.

2. A diaper comprising an elongated body member shaped to pass through the crotch and up the front and back of an infant, said body member having at its intermediate portion a pad-receiving pocket having inner and outer sides integral with and forming part of the body member, the inner side of the pocket having an opening located substantially centrally of the pocket, the dimension of which opening both lengthwise and transversely of the body member is less than that of the pocket, a protective envelope loosely received within the pocket but unattached to the body member and removable from the pocket through the pocket opening, said envelope having inner and outer sides formed of material which is impervious to water and forming between them a compartment and also having an opening in the inner side leading to said compartment, which opening is substantially the same size as and registers with the pocket opening, the inner ply of the body member covering all of the inner side of the envelope surrounding its opening, and a pad of absorbent material removably retained within the compartment of the envelope, a portion of said pad being exposed through the registering openings, said envelope with its enclosed pad being removable from the pocket of the body member through the pocket opening and when in the pocket completely protecting both the inner and outer plies of the body member against moisture that may be absorbed by the pad.
